UNITED STATES PATENT OFFICE

101,136

DESIGN FOR A REFRIGERATOR SHELF

Frank D. Peltier, Newburg, Ind., assignor to
Servel, Inc., New York, N. Y., a corporation of
Delaware

Application September 14, 1935, Serial No. 58,551

Term of patent 14 years

To all whom it may concern:

Be it known that I, Frank D. Peltier, a citizen of the United States, residing at Main Street, city of Newburg, county of Warrick and State of Indiana, have invented a new, original, and ornamental Design for a Refrigerator Shelf, of which the following is a specification, reference being had to the accompanying drawing, forming part thereof.

The figure is a perspective view of a refrigerator shelf showing my design.

The characteristic feature of my invention

resides in a frame member of substantially rounded cross sectional configuration and with spaced groups of flat bars extending in parallel relation transversely of the same, each group of bars being composed of an intermediate relatively wide member and a single narrower member at each side of the same, as shown.

I claim:

The ornamental design for a refrigerator shelf as shown and described.

FRANK D. PELTIER.
